PAGE 2

Fig. 1 is a perspective view of an automobile grille, showing my new design. A portion of an automobile shown in broken lines is for the purpose of illustration only;

Fig. 2 is a front elevational view of the automobile grille;

Fig. 3 is a top plan view of the automobile grille;

Fig. 4 is an enlarged fragmentary side elevational view;

Figs. 5, 6 and 7 are enlarged sectional views taken substantially through the lines 5—5, 6—6 and 7—7 of Fig. 2 looking in the direction of the arrows;

Fig. 8 is an enlarged fragmentary front elevational view of the portion of the grille circumscribed by the circle 8 in Fig. 2; and

Figs. 9, 10, 11, and 12 are enlarged sectional views taken substantially through lines 9—9, 10—10, 11—11, and 12—12 of Fig. 8 looking in the direction of the arrows.

I claim:

The ornamental design for an automobile grille, substantially as shown and described.
